[57] CLAIM

The ornamental design for a substrate clamp for a slitting apparatus, as shown.

DESCRIPTION

FIG. 1 is a perspective view of a substrate clamp for a slitting apparatus showing my new design;
FIG. 2 is a left side elevational view thereof;
FIG. 3 is a right side elevational view thereof;
FIG. 4 is a front elevational view thereof;
FIG. 5 is a top plan view thereof; and
FIG. 6 is a rear elevational view thereof.

FIG. 1

FIG. 2

FIG. 3
